Fig. 2

Fig. 3

Fig. 4

Fig. 5

Fig. 6

FIG. 1 is a perspective view of a rake head showing our new design;

FIG. 2 is a rear elevational view;

FIG. 3 is a bottom plan view;

FIG. 4 is a side elevational view;

FIG. 5 is a sectional view taken on line 5—5 of FIG. 2; and

FIG. 6 is another sectional view taken on line 6—6 of FIG. 2.

The fragmentary rake handle in FIGS. 1 and 4 is depicted for purposes of illustration only.

We claim:

The ornamental design for a rake head, as shown and described.
